UNITED STATES PATENT OFFICE.

EDWARD A. WARNER, JR., OF MILLBURN, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed November 22, 1927. Serial No. 234,981.

My invention relates to railway traffic controlling apparatus, and particularly to apparatus of the type comprising train carried governing means controlled by inductors located at intervals along the trackway. More particularly my present invention relates to the trackway portion of such apparatus.

I will describe one form of trackway apparatus embodying my invention, and will then point out the novel features thereof in claims.

The accompanying drawing is a diagrammatic view illustrating one form of trackway apparatus embodying my invention.

Referring to this drawing, the reference characters 1 and 1^a designate the track rails of a stretch of railway track over which traffic normally moves in the direction indicated by the arrow. These rails are divided, by means of insulated joints 2, to form a plurality of track sections A—B, B—C, etc. Each track section is provided with a track battery designated by the reference character F with an appropriate distinguishing exponent and connected across the rails adjacent the exit end of the section. Each section is also provided with a track relay designated by the reference character R with a suitable exponent and connected across the track rails adjacent the entrance end of the section.

Each track section is also provided with a trackway signal designated by the reference character S with an appropriate exponent. In the form here shown each of the signals S is of the semaphore type, and is located adjacent the entrance end of the corresponding section, but this particular form and arrangement of signals is not essential. The circuits for controlling the signals form no part of my present invention and have been omitted from the drawing for the sake of simplicity.

Associated with each section is a slow-acting relay, designated by the reference character J with an exponent corresponding to the location, and controlled by the track relay for the section next in rear. Referring for example to relay J^B, this relay is normally de-energized but when a train enters section A—B, relay R^A becomes de-energized and current then flows from terminal D of a suitable source of energy not shown in the

drawing, over back contact 3 of relay R^A, wires 4 and 5, and winding of relay J^B to terminal E of the same source. Relay J^B therefore becomes energized, but due to its slow acting characteristics, an interval of time elapses before the relay closes its front contact. Associated with relay J^B is a line relay H^B, which is arranged to be energized when relay J^B closes, provided track relays R^B and R^C are both energized. The circuit for relay H^B may be traced from terminal D, through front contact 6 of relay R^C, wire 7, front contact 8 of relay R^B, wire 9, front contact 10 of relay J^B, wire 11, and winding of relay H^B to terminal E. Each of the remaining sections is provided with a line relay H which is controlled by circuits similar to the circuit just traced for relay H^B.

Each track section is provided with a trackway inductor comprising a core 20 provided with a winding 21 and located adjacent the entrance end of the corresponding section. The inductors K are suitable for co-operation with train carried governing means in such manner that when a train passes an inductor K having its winding 21 open-circuited, a stop indication is received on board the train. If the winding 21 of the inductor K is shunted, however, when the train passes the inductor, the train does not receive a stop indication. The winding 21 of each inductor K is controlled by an auxiliary relay designated by the reference character G with an appropriate exponent.

Referring particularly to relay G^B, this relay is provided with a pick-up circuit which may be traced from terminal D, through wire 13, front contact 14 of relay H^B, wires 15 and 16, and winding of relay G^B to terminal E. The relay G^B is also provided with a stick circuit which passes from terminal D, through back contact 3 of relay R^A, wires 4 and 17, front contact 18 of relay G^B, wires 19 and 16, and winding of relay G^B to terminal E. It is manifest, therefore, that when relay H^B becomes energized, the pick-up circuit for relay G^B is closed, and that relay G^B is subsequently maintained in its energized condition as long as relay R^A is de-energized. Winding 21 of inductor K^B is provided with a shunting circuit which may be traced from the right-hand terminal of the winding 21, through wire 22, front contact 23 of relay G^B, and wire 24 back to

the left-hand terminal of winding 21. It follows, therefore, that when relay G^B is energized, the shunting circuit for inductor K^B is closed and a train passing the inductor 5 under these conditions will not receive a stop indication. The control of each of the remaining relays G is similar to the control of relay G^B and will be readily understood from the drawing.

10 As shown in the drawing, the stretch of track is unoccupied, so that all of the track relays are energized and all of the slow-acting relays J are de-energized. All of the relays H and all of the relays G are de-energized and the shunting circuit for each inductor K is open.

15 In explaining the operation of the apparatus as a whole, I will first assume that a train enters section A—B. Relay R^A then 20 opens, closing, at back contact 3 thereon, the circuit for relay J^B . At the expiration of the time interval required for the operation of this relay, front contact 10 closes and since relays R^B and R^C are both energized, 25 relay H^B then picks up. The closing of front contact 14 of relay H^B completes the pick-up circuit for relay G^B , which thereupon closes to complete the shunting circuit for inductor K^B . When the train enters 30 section B—C, therefore, passing the inductor K^B , it will not receive a stop indication. The parts are so adjusted that the time interval required for relay J^B to close its front contact is equal to the time required by a train 35 travelling at the maximum permissive speed to move from point A to point B. If a train, travelling at a greater speed than the maximum permissive speed, traverses the stretch of track, it will reach point B before the relay J^B has closed its front contact. 40 As soon as the train enters section B—C, relay R^B opens, and if front contact 8 of relay R^B opens before front contact 10 of relay J^B closes, relay H^B remains de-energized 45 and the pick-up circuit for relay G^B remains open. Under these conditions the shunting circuit for inductor K^B remains open and the train will receive a stop indication as it passes inductor K^B . It will be seen, therefore, that if traffic conditions in advance are 50 safe, that is, if section B—C and the section to the right are both unoccupied, a train travelling at a speed less than the maximum permissive speed, will receive a proceed indication as it passes the inductor K^B . If the train is exceeding the maximum permissive speed, or if a train occupies section B—C or the section to the right of point C, the shunting circuit for inductor K^B will not 55 be closed and the train will receive a stop indication as it passes the inductor K^B .

60 Apparatus embodying my invention is particularly suitable for operation on rapid transit lines in which the trains are made up of a plurality of cars each provided with 65

train carried governing means controlled by a trackway inductor. In installations of this character, it is obvious that the shunting circuit for the inductor K^B must be kept closed until the rear of the train has passed 70 the inductor. It will be observed that after a train moving slower than the maximum permissive speed, has entered section B—C, relay R^B opens and de-energizes relay H^B . The pick-up circuit for relay G^B is then interrupted but relay G^B is now held closed by virtue of its stick circuit including back contact 3 of relay R^A . Relay G^B therefore remains closed to complete the shunting circuit for inductor K^B as long as any portion of the 80 train occupies section A—B. When the rear of the train passes out of section A—B, relay R^A becomes energized, thereby breaking the stick circuit for relay G^B and allowing this relay to open. At the same time the 85 relay J^B becomes de-energized to restore the apparatus to its normal condition. The operation of the apparatus as the train proceeds through section B—C will be understood without further explanation. 90

95 Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

100 1. In combination, a forward and a rear section of railway track, an inductor located in the trackway adjacent the junction of said sections and comprising a winding, means set into operation when a train enters said rear section and effective if at least a predetermined time interval elapses before the train enters the forward section to close a shunting circuit for said winding, and means for subsequently holding said circuit closed as long as any part of the train occupies said rear section. 105

110 2. In combination, a forward and a rear section of railway track, an inductor located in the trackway adjacent the junction of said sections and comprising a winding, a slow acting relay having a circuit arranged to be closed when a train enters the rear section, a line relay controlled by said slow acting relay and by traffic conditions in the forward section, an auxiliary relay for controlling said winding, a pick-up circuit for said auxiliary relay controlled by said line relay, and a stick circuit for said auxiliary relay controlled by traffic conditions in the rear section. 115

120 3. Railway traffic controlling apparatus comprising a stretch of railway track divided into sections, a track circuit for each section including a track relay, a slow acting 125

relay for each section controlled by the track relay for the section next in rear, a line relay for each section controlled by the associated track relay and associated slow 5 acting relay and by the track relay for the section next in advance, an auxiliary relay for each section, a pick-up circuit for each auxiliary relay including a front contact of the adjacent line relay, a stick circuit for 10 each auxiliary relay including its own front

contact and a back contact of the track relay for the section next in rear, an inductor located in the trackway adjacent the junction of each two sections and each comprising a winding, and a shunting circuit for 15 each said winding including a front contact of the adjacent auxiliary relay.

In testimony whereof I affix my signature.

EDWARD A. WARNER, JR.
